I. M. LYON.

SAFETY GOVERNOR CONTROL MECHANISM

Filed March 11, 1924

FIG. 1.

FIG. 2.

UNITED STATES PATENT OFFICE.

IVEY M. LYON, OF HUNTINGTON BEACH, CALIFORNIA.

SAFETY GOVERNOR-CONTROL MECHANISM.

Application filed March 11, 1924. Serial No. 698,424.

This invention relates to governor control mechanisms, and is more particularly directed to a governor control mechanism adapted to be employed in connection with a hit-and-miss, balanced, two-weight type governor as adapted to gas engines.

The control mechanisms now employed in connection with the hit-and-miss type governors are so constructed that when it is desired to adjust or enable a quick change of speed of the gas engine, it is necessary to reach over or around the fly-wheel to unlock a locking device which holds a governor adjustment set. With this arrangement many accidents have occurred and in several cases the operators of these gas engines have lost their hands while attempting to change the adjustment of these governors or to release the locking device so that the speed of the gas engine might be varied. Because of these numerous accidents, the Government now requires that the gas engines be enclosed in a cage, and that the engine be stopped before any regulation of the governor may be effected or the locking device released so that the speed of the gas engine may be changed. It is obviously disadvantageous to try to regulate the speed of these gas engines when the same are idle.

Therefore, an object of this invention is to provide a governor control mechanism that may be regulated while the engine is in motion from a point distant thereto.

An object of this invention may be to provide a means of control of a hit-and-miss governor which is effectively and easily operated at a point distant from a gas engine.

A further object of this invention is to provide a means of setting and locking the adjustment of these hit-and-miss governors at a point distant from the gas engine.

Other objects and advantages will be apparent from the following detailed description of a preferred embodiment of this invention as illustrated in the accompanying drawing.

In the drawing:

Figure 1 is a side elevation of a gas engine illustrating a hit-and-miss governor embodying this novel control mechanism.

Fig. 2 is an enlarged fragmental side elevation, partly in section, of a governor control mechanism embodying this invention.

Fig. 3 is a side elevation, partly in sec-

tion, of a governor control mechanism embodying this invention, taken from the opposite side of Figure 2.

Fig. 4 is a sectional view taken substantially on the line 4—4 of Figure 3.

A gas engine is diagrammatically illustrated at 1, having a fly-wheel 2 adapted to drive a hit-and-miss type governor 3, by means of a gear 4, which gear 4 meshes with a governor gear 5, to which gear 5 a pair of balanced weights 6 are pivoted and connected in a manner well known in the art so that with an increase in speed of the fly-wheel 2 the weights 6 are thrown outward against the tension of a spring 7. A governor actuating cam 8 is adapted to slide radially outward in a groove 9 in the gear 5 when the balanced weights 6 are thrown radially from the center by an increased rate of speed of the fly-wheel 2. The cam member 8 is adapted to engage a pick lever roller 10, which pick lever roller 10 is journaled on a suitable pin 10^a, which pin 10^a is secured to one end of a pick lever 11. The pick lever 11 is pivoted to a pivoted arm 12, which arm 12 is pivoted to the case supporting the connecting rod 17 as illustrated in Fig. 3 and when the cam member 8 strikes the pick lever roller 10, the end of the pick lever 11 is thrown upward in a manner to cause the end 13 to be thrust downward to engage an abutment 14 in such a manner as to hold the exhaust valve 15 open so that the gas engine 1 will not draw an explosive charge of mixture into the cylinder and will fail to fire. This operation is well understood in the art and it is not deemed necessary to further describe this action, as this invention relates to a means for adjusting the position of the roller pin in relation to the cam member 8; it being, of course, understood that the cam 16 operates to open the exhaust 15 through a suitable connecting rod 17, and that a suitable pressure member 29 acts to release the pick lever 11 from engagement with the abutment 14 when the cam member 8 fails to engage the pick lever roller 10 due to the engine slowing down.

The position of the pick lever roller 10 is preferably regulated in relation to the cam 8 by the following means:

An actuating arm 18 pivotally supported as illustrated at 21 is provided with an arcuate slot 19 at its lower end, in which 110

slot 19 a pin 20 is adapted to ride, and which pin 20 is secured to the upper end of the arm 12. The lowest point of the slot 19 is at the end of the slot nearest the pivot point of the arm 12 so that as the slot 19 is rotated in one direction, the end of the arm 12 carrying the pin 20 is raised and when the slot 19 is rotated in the opposite direction the same end of the arm 12 is lowered. The roller 10 being mounted on the lever 11 which is pivoted to the arm 12 on a pin 10^a is by this means raised or lowered so that the cam member 8 strikes the roller 10 at intervals depending on the position of the roller 10 and thereby regulates the speed of the engine 1. Near the upper end of the arm 18 a rod 22 is pivoted as illustrated at 23, and which arm 22 extends outward from the engine 1 and is adapted to slide in a bracket 23^a.

It will be obvious that by moving the rod 22, the height of the pick lever roller 10 will be varied so that the speed of the gas engine may be regulated.

In order to provide a permanent adjustment of speed, I prefer to provide a locking means, as illustrated at 24, to hold the rod 22 in permanent set position when the gas engine 1 is actuating a well pump, which locking means is illustrated as comprising a screw clamp 27 and a hand screw 28.

It is often desirable, especially in the case where these gas engines are used in connection with oil well equipment, to have a connection whereby the speed of the gas engine may be quickly varied at a point distant to the engine. For this purpose I prefer to provide a cable 25, one end of which may be extended into the oil well rig, and the other end of which may be provided with a suitable weight 26, the weight 26 acting to pull the lever 18 toward the front of the engine 1, thereby reducing the speed of the gas engine 1. The cable 25 provides an alternative control to be used when it is desired to quickly and at frequent intervals vary the speed of the engine 1, while the rod 22 and clamp 27 serve as an adjustable control for setting the speed of the engine 1 when the same is used for pumping purposes and the like.

Having fully described a preferred embodiment of this invention, it is to be understood that I do not wish to be limited to the exact mechanism herein disclosed, but

my invention is for the scope of the appended claims.

I claim:

1. A hit-and-miss governor comprising a gear driven from a fly-wheel, balanced weights pivoted to the gear, a cam member adapted to slide in a slot in the gear, an exhaust valve, means to open the exhaust valve, means operated by the cam member for actuating the exhaust valve control means, said latter means comprising a control rod having an arcuate slot, a pin adapted to ride in the slot, a roller carried by the pin, means mounted in connection with the said roller for holding the exhaust valve open when the roller is engaged by the cam member and means operable from a distance to regulate the position of the roller in relation to the cam member.

2. In a hit-and-miss governor, the combination of a driven gear, balanced weights pivoted to the gear, a recess in the gear, a cam member adapted to slide in the recess, a pick lever, a roller carried by the lever for engagement with the cam member, a pivoted arm, means pivotally connecting the pick lever to the pivoted arm, a control lever pivoted intermediate its ends and means secured to the pivoted control lever in an off center position and adapted to actuate the said pivoted arm to raise or lower the said roller so as to regulate the position of the roller in relation to the cam member substantially as and for the purpose described.

3. The combination with a hit-and-miss governor having a pick lever, a pick lever roller, and a cam member, of a control mechanism comprising a control lever, a guide at the lower end of said lever, and means operated by the control lever guide by rotation of the control lever for varying the position of the pick lever roller in relation to the said cam member.

4. The combination with a hit-and-miss governor, having a pick lever, a pick lever roller, and a cam member, of a control lever, an arcuate slot at the lower end of said lever, and means actuated by the rotation of the arcuate slot for varying the position of the pick lever roller in relation to the cam member.

Signed at Los Angeles, California, this 3d day of March 1924.

IVEY M. LYON.
